FEEDING DEVICES FOR PRESSING AND OTHER MACHINES

George Frederick Clark, West Drayton, England

Application March 24, 1954, Serial No. 418,426

5 Claims. (Cl. 271—2.5)

This invention relates to feeding devices for machine tools such as punch presses and the like and has particular reference to such a device which comprises a reciprocable carrier, operable by a machine tool, and mounting a blade or element which is adapted to engage the material to be fed during the forward stroke of the carrier, and thereby feed the material to the tool.

The object of the present invention is to provide a device of the above mentioned character which is positive in its action and which provides for the easy insertion of the material into the device and its removal therefrom.

With the above and other objects in view the invention consists in providing a device for feeding strip material into pressing and other machine tools comprising a base carrying a spring loaded lever adapted to be actuated by a device connected with the machine tool, a feeding blade connected with the lever, a reciprocable carrier for the feeding blade, manually operable means adapted to be moved towards or away from the feeding blade and means to hold the material during the return stroke of the carrier, the arrangement being such that the material can be inserted into the feeding device or removed therefrom from one side of the said feeding device.

The invention also consists in providing a device wherein the feeding of the material is effected by the movement of the lever in one direction and the return or non-feeding stroke of the gripping mechanism is effected solely by the spring connected with the lever.

The invention further consists in providing a feeding device for a machine tool comprising a base having an upstanding part at one end which pivotally mounts a spring loaded lever, means on the lever whereby it may be oscillated on its pivots by a machine tool engaging the said means, a link connecting the lever to a feeding blade carried by a reciprocable carrier slidable on the base and disposed to one side thereof, a manually operable member on the carrier adapted to be moved towards or away from the feeding blade, a spring loaded rockable blade disposed at the other end of the base, and a manually operable member adapted to be moved towards or away from the spring loaded blade, the arrangement being such that strip material may be inserted into the device from one side thereof to be engaged by the blades and held therein by the engagement therewith of the manually operable members, the feeding blade serving to grip the material during the feeding stroke of the carrier and the other blade acting to hold the material during the return stroke of the feeding blade.

The invention also includes means whereby the blades may be adjusted to suit various thicknesses of material, and means, for the support of the material, which is adjustable for different widths and thickness of material.

The invention will now be described, by way of example, with reference to the accompanying drawings, in which:

Figure 1 is a side elevation of a feeding device in accordance with the present invention;

Figure 2 is a plan thereof;

2

Figure 3 is a vertical section on line III—III of Figure 2;

Figure 4 is an end elevation in the direction of the arrow "A";

5 Figure 5 is a section on line V—V of Figure 2, irrelevant parts beyond the section plane being omitted;

Figure 6 is a perspective view of the feeder blade and its mounting;

10 Figure 7 is a perspective view of the holding blade and its mounting;

Figure 8 is an elevation of the reciprocating carrier viewed from the direction of the arrow "B" of Figure 2 and

15 Figure 9 is a fragmentary detail showing a part of the underside of the carrier and the spring which imparts friction between the slide and the carrier and so prevents any side play of the carrier while it is being reciprocated and to ensure the gripping blade operating before the movement of the carrier.

20 20 As shown the device for feeding stock such as strip material into a machine tool such as a press tool comprises a base 1 having an upstanding hollow casing 2 formed with a lug 3 in which is mounted for oscillation a spindle 4 of a lever 5 carrying at its upper end a

25 roller 6 adapted to be engaged by the press tool, not shown. This lever 5 is conveniently in the form of a box-like structure and its upper end is fitted with a spindle 7 on which the roller 6 is mounted for rotation preferably on needle rollers or other anti-friction means. To

30 30 the lower end of this lever 5 is connected pivotally a link 8 connected to a pin-like extension 9 of a crank member 10 formed with a feeding blade 11. This crank member 10 is mounted in a manner to be hereinafter described in a carrier 12 adapted to reciprocate on a

35 35 plate or slide member 13 secured at one end by screw members 14 to the base 1. This carrier 12 is adapted to be moved forwardly to feed strip material indicated at 15 into the press tool when the lever 5 is actuated by for instance a cam or other means, not shown, engaging the

40 40 roller 6. This forward feeding is effected against the action of a spring 16. Conveniently this spring 16 in the form of a coiled tension spring is connected at one end to a lug 17 formed on the lever 5 and at its other to a lug 18 screwed into the base 1 the spring 16 being

45 45 mounted within the hollow casing 2. An adjustable stop 19 adapted to be actuated by a micrometer 20 is fitted in the base 1 to limit the rearward movement of the carrier 12. This carrier 12 preferably in the form of a casting is formed with a lug or extension 21 to engage

50 50 50 the stop 19, and is also formed on its lower side with a recess 22 having surfaced side walls 23 to slide on the sides of the plate or slide member 13. The lower end surfaces of the side walls 23 are arranged in line with the underside of the plate or slide member 13 and to

55 55 55 these lower end surfaces are fitted surface plates 24 and 25 to co-operate with the underside of the plate member 13 and thus prevent any upward movement of the carrier 12. To prevent any sideway movement one side 23 is formed with a recess 26 in which is mounted a spring 27 comprising a flat surface to co-operate frictionally with one side of the plate or slide member 13 and having spring-like curved extensions 28 to engage in the recess. The base of this recess 26 is closed by the surface plate 25. The other surface plate 24 is

60 60 60 slotted at 29 for the reception of the pin-like extension of the crank member 10. These surface plates 24 and 25 are held in position by screws 30 preferably having milled heads and hexagonally shaped recesses for the insertion of a tool of similar shape whereby they may be firmly

65 65 65 secured to hold the surface plates or readily unscrewed for removal. The crank member 10 formed with the feeding blade 11 has its spindle 31 mounted eccentrically

in a sleeve 32 rotatably mounted in a recess 33 formed in the casting of the feed carrier 12. This sleeve 32 which carries the crank member 10 having the feeding blade 11 shown more particularly in Figure 6 is cut away at 34 for the feeding blade 11 and is divided at 35 to facilitate assembly. The outer end of this sleeve 32 is formed with a slot 36 whereby it may be adjusted by a screwdriver to raise or lower the feeding blade 11 which is formed with a knife edge 37 to engage the strip material 15. To prevent axial movement of the sleeve 32 it is formed with a circumferential groove 38 in which is mounted the end of a screw 39 threaded into the side of an upper extension of the feed carrier 12. In order to enable the strip material 15 to be fed into the side of the feeding device and to maintain it in position to be engaged by the feeding blade 11 the carrier 12 is fitted with an anvil-like device comprising a pressure block 40 pivotally mounted at 41 in a forked bracket 42 formed on the carrier 12. This pressure block 40 is pivotally connected by means such as links 43 to a forked end of a handle lever 44 having a fulcrum 45 in the bracket 42. These links 43 are pivoted at 46 to the pressure block 40 and at 47 to the forked end of the handle lever 44. Thus the handle lever 44 when in its raised position will permit the strip material 15 to be inserted in the device and will when lowered to beyond its dead centre maintain the pressure block 40 on the strip material 15 so that it can be engaged by the feeding blade 11. This arrangement thus provides an adjustment for the thickness of the strip material. In order to prevent backward movement of the strip material the main base casting 1 is fitted with a further knife edged blade 48. This blade 48 is adapted to pivot on a spindle 49 formed eccentrically on a sleeve 50 rotatably mounted in a cylindrical recess 51 formed in the base casting 1. This blade 48 and its carrying sleeve 50 is shown more particularly in Figure 7. The outer end of the sleeve 50 is formed with means such as a slot 52 whereby it may be adjusted by for instance a screwdriver to raise or lower the blade. To prevent axial movement of the sleeve 50 it is formed with a circumferential groove 53 in which is mounted the end of a screw 54 threaded into the base 1. The blade 48 is normally held in its raised position by pressure of a coiled spring 55 engaging through the medium of a pin 56 a curved or part spherical extension 57 of the blade member 48. Above the blade 48 is fitted a further anvil-like device comprising a pressure block 58 pivotally mounted at 59 in a forked bracket 60 formed on the base casting 1. This pressure block 58 is connected by links 61 to the forked end of a handle-lever 62 having a fulcrum 63 in the bracket 60. This anvil-like device is similar to the other anvil device previously described and is adapted to be operated in a similar manner. Thus the blade 48 will turn against the action of the spring 55 to permit the strip material to be moved forwardly by a gripping blade 11 but any rearward or return movement will be prevented by the blade 48 engaging the strip material. In order to prevent side displacement of the material while passing through the device a transversely adjustable forked-like carrier 64 is mounted on the base 1. This carrier 64 is fitted at one end with a rotatably mounted guide roller 65 and a similar guide roller 66 is mounted on the base 1. This latter roller 66 is adapted to rotate on a cylindrical sleeve 67 mounted on a stud 68 screwed into the base 1. The carrier 64 is slotted at 69 throughout its length so that it can be slid under the sleeve 67 of the roller 66 and under an L shaped guide plate 70 carried by the lug 18 to which the end of the spring 16 is secured. Thus the outer guide roller 65 can be adjusted according to the width of the strip material. When the strip material is in position between the guide rollers 65 and 66 the stud 68 carrying the latter roller 66 can be screwed down to secure the forked carrier 64 in its adjusted position. The base 1 and the slide plate 13 are provided with apertures 71 whereby the above described feeding device can be secured on or adjacent to the press tool 75

or the like. The stop 19 which is adapted to be actuated by the micrometer 20 to limit the rearward movement of the carrier 12 is formed with a longitudinal groove to receive the end of a screw 72 to prevent its rotation when adjusted by the micrometer 20.

In operation and when the device is being put to use, the levers 44 and 62 are lifted and the material 15, strip metal for instance, is placed on the blades 11 and 48 and rested on the surface at the end of the base and on the carrier 64 which is adjusted so that the rollers 65 and 66 engage the side edges of the strip. The levers 44 and 62 are then moved downwardly to cause the anvils 40 and 58 respectively to press the strip 15 onto the blades. As soon as the device is set in motion by the press machine engaging the roller 6 of the lever 5 the pull on the link 8, connected to the feeder blade 11 causes the latter to tilt so that its knife edge 37 thereof bites slightly into the strip 15 so that it is gripped. The carrier 12 together with the feeder blade 11 is then drawn forward to feed the strip into the press. At the commencement of the return stroke of the carrier 12, the feeder blade 11 is initially tilted so that the gripping action is relaxed thus enabling the carrier 12 to return to its former position without drawing the strip with it. It will be seen that the friction of the carrier 12 with the plate or slide member 13 is such that the initial movements of the feeder blade 11 can take place before the carrier 12 commences to move. In order to effect a fine adjustment of the amount of grip, the angular position of the blade may be adjusted as previously described through the medium of its eccentric mounting.

So that a minute adjustment of the amount of feed may be made, the movable stop 19 is adjusted by the micrometer 20 which projects beyond the base 1 and is furnished with the usual hub and thimble, for the adjustment of the stop.

It will be understood that the blade 48 to prevent return or backward movement of the stop is so spring loaded, preferably by its torsion spring 55, that the edge of the blade is constrained to grip the strip material when inserted between the blade and anvil. The blade 48 is inclined in the direction of the feed, consequently it offers but little resistance to the forward movement of the strip, but any tendency for the strip to move back during the return stroke of the carrier will cause the blade to tilt and grip the strip owing to the action of the spring, and thus prevent any such backward movement of the strip. The extent to which the strip may be gripped may be adjusted by partial rotation of the sleeve 50 as previously described. It will be seen that height of both of the blades 11 and 48 can be readily adjusted owing to their eccentric mounting.

It will be clear from the foregoing description that a strip of material can be quickly inserted in the feeder device from one side thereof and just as easily removed, whereas in other feeding devices it has been necessary to thread the material through the device from one end which operation takes some appreciable time. One advantage of the device according to the present invention, is that, should it be necessary to re-position the material being fed to a machine tool, the operation can be speedily done.

Previous feeding devices rely upon the spring to feed the material. In this device the spring is used to return the gripping mechanism only and the press or punching machine provides the power used for feeding the material.

What I claim is:

1. A feeding device for a machine tool comprising a base, an upstanding part at one end thereof, a spring loaded lever pivotally mounted on said part, means on the lever whereby it may be oscillated by a machine tool engaging said means, a reciprocable carrier slidably mounted at one side of the base, a feeding blade on said carrier, a link connecting the lever to the feeding blade,

a manually operable member mounted on the carrier for movement toward and from the feeding blade, a rockable spring loaded blade at the other end of the base, and a manually operable member movable toward and from the rockable blade, the feeding blade being connected to a crank member, a link connecting the crank member and spring loaded lever, the crank member being eccentrically mounted in a sleeve, and the sleeve rotatably mounted in the carrier, means being provided to maintain the sleeve in various positions.

2. A device as claimed in claim 1, wherein the sleeve is cut away to receive the feeding blade, is split at one end to facilitate assembly and the other end is provided with a tool receiving formation for adjustment, and a circumferential groove is formed in the sleeve for the reception of locking means, locking means being provided therefore.

3. A device as claimed in claim 1, wherein a sleeve is rotatably mounted in the base, a spindle is formed eccentrically on the sleeve, the spring loaded blade is pivotally mounted on the spindle, and means are provided to adjust and maintain the sleeve in axially rotated positions, to adjust the height of the said blade.

4. A device as claimed in claim 1, wherein the manually operable member includes a pivotally mounted pressure block, said block being carried by a bracket, said bracket being mounted on the carrier, and means are

5 provided for operating the same including link means comprising dead center mechanisms connecting the block to a handle lever, the handle lever being fulcrumed in the bracket, whereby manipulation of the said means by

10 the lever to operate the link means effects gripping action of the block against material being fed and thereby against the blade.

15 5. A device as claimed in claim 1, wherein the manually operable member comprises a pressure block, a bracket is formed on the base, the block is pivotally mounted in the bracket, a handle lever is fulcrumed in the bracket, and links connect the block to the lever, manipulation of the lever causing the pressure block to engage material to be fed and hold the same in contact with the spring loaded blade.
